UNITED STATES PATENT OFFICE.

EDWIN LETTS OLIVER, OF PIEDMONT, CALIFORNIA.

METHOD OF FORMING PROTECTIVE LININGS.

Application filed January 30, 1923. Serial No. 615,946.

To all whom it may concern:

Be it known that I, EDWIN LETTS OLIVER, a citizen of the United States, and a resident of Piedmont, county of Alameda, 5 State of California, have invented new and useful Improvements in Method of Forming Protective Linings, of which the following is a specification.

My invention has for its object the lining of structures otherwise liable to corrosion and is particularly applicable to metal or wooden structures such as tanks, vats, vessels, and the like, whereby the said structures are suitably protected from any 15 corrosive liquid or gaseous substances, confined in or traveling through the said structures.

My invention is also particularly applicable to protection against erosion of cutting material. It is well known that mining slimes, particularly those of an abrasive nature, and material containing quartz generally, as also mixtures employing abrasives in industries as emery and carborundum, 20 have a particularly erosive action upon steel or metallic containers or conduits and in such cases the application of a rubber lining as here set forth forms a complete protection to the metallic supporting structure whether it be a trough, tank or conduit.

These objects I accomplish by covering the inner surface of such a structure with a coating of relatively elastic material, held 35 in place by means of wire netting or mesh, or sheet metal screen, and which has been previously affixed to or formed in the body of the structure to be protected.

By referring to the accompanying drawings, my invention will be made clear.

Figure 1 is a cross section of a conventional tank of sheet metal to which my protecting lining has been applied.

Fig. 2 is a front view of the wire netting and screws in place ready for fastening.

Fig. 3 is an enlarged cross section through a portion of the wall of the tank with the wire mesh in place thereon and the coating of protective material being applied.

Fig. 4 is a front view of sheet metal punched for receiving the protective coating and adapted to be used in the same way as the wire netting 2.

Fig. 5 is a section through a plate such as Fig. 4 to which the protective coating has been applied.

As is well known, rubber has especially valuable resisting qualities to the action of acid, alkalis or abrasive substances in motion, and in the figures above set forth I 60 have assumed the use of rubber as the non-corrosive and non-erosive substance to be employed as the lining, although it will be understood that other relatively elastic substances may be employed in the same 65 manner.

Throughout the figures similar numerals refer to identical parts.

The numerals 1, 1 indicate the walls of a tank or vat of iron, steel or wood supported on sills 2, 2, 2, 2, and having my rubber or other protective lining 3, by which the contents 4 is prevented at all times from coming in contact with the side walls 1 or bottom 5 of the said tank. At 6 is shown a wire mesh or netting which is superimposed upon the interior surface of the walls and bottom 5 and preferably carried over the upper edge thereof as shown at 7 in Fig. 1. This wire mesh is suitably anchored at various points as 8, 8, as by spot welding or riveting to the surface 1 if the latter is of metal, or it may be fastened by a screw 9 into a wooden tank or vat wall 1 as shown in Fig. 3, and if the space to be protected is a relatively large area or the wire mesh of relatively light weight, it is advantageous to support the mesh 6 in spaced relation to the plate or wall 1, by 80 the employment of the spacing rings or 85 blocks 10.

The protective material 3 I employ in a plastic state, preferably in the form of sheets for laying against the wire mesh as 90 shown in Fig. 3. When the sheets are in place I employ a roller 11, or other suitable pressing means, whereby the plastic material is pressed against and flows around the individual wires of the wire mesh, thus 95 securing an embedding of the mesh in the said plastic material and consequently a reinforcing of the latter. The rubber can then be vulcanized in place in any well known manner.

By referring to Fig. 3 it will be seen that the plastic material under the action of the pressure above described flows through the opening and around the wire mesh or edges of the metal plate, at all points except where the mesh is in contact with or is held against the container surface, and at these latter points its full thickness is 105 110

maintained over the rivet or screw head as the case may be.

It will thus be seen that the tank shown in Fig. 1 has a complete lining of non-corrosive and non-erosive protective material which prevents the contents 4 from acting upon any portion of the supporting structure, as the walls 1 or bottom 5, and that in effect all of the stresses and strains due to the weight or of the contents are fully taken care of by the walls and bottom of the container and the protecting lining serves at all times to protect the said structure from corrosive or erosive action or both.

In some instances it is advantageous to employ punched sheet metal in place of the wire screen for the purpose of supporting the protecting lining and in such case a screen such as shown in Fig. 4 may be employed and which may be spot welded or riveted at intervals or otherwise supported from the wall of the tank. The protective material may then be placed upon both sides of such a screen and pressed through the holes so that the two layers of protective material are in effect welded together through the interstices of the metal screen. This plate form of supporting the lining shown in Fig. 4 has the advantage of being subject to less distortion, especially for temperature changes, and also provides frequent points of support for the non-corrosive lining as at each of its perforations. Moreover in certain structures the body of the tank itself may be formed of such metal screen as shown in Fig. 4 or a section as shown in Fig. 5.

Although I have described my invention

as applied to a tank and to prevent the corrosive or erosive action of the contents upon the surfaces of the tank, it will now be seen that my invention may also be employed in troughs, containers or conduits, in which the liquid contents is completely sealed from the metallic walls by my coating.

I claim:

1. The method of protecting a surface which consists of securing a supporting screen over said surface at a plurality of points and in spaced relation therewith and thereafter overlaying said screen by pressing a plastic rubber composition over the screen until the said screen is embedded in said composition, and then vulcanizing said rubber in place.

2. The method of providing a container with a non-corrosive lining which consists of securing a metallic screen to a surface of said container by affixing it at a plurality of points and in spaced relation with said surface, and thereafter pressing plastic rubber around the screen and against said surface so that the mesh is entirely embedded in the rubber, and then vulcanizing said rubber in place.

3. The method of providing a container with a non-corrosive lining which consists of affixing a perforated backing to the inner surface of said container in spaced relation thereto, thereafter pressing plastic rubber against said backing and thereby forcing a part of it through the perforations against said container while the remainder entirely overlays the backing to form a lining and then vulcanizing the rubber in place.

EDWIN LETTS OLIVER.
